(57) **CLAIM**

The ornamental design for a cooking device, as shown and described.

DESCRIPTION

FIG. 1 is a front perspective view of the cooking device; FIG. 2 is another front perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; and, FIG. 9 is a bottom perspective view thereof.

In some implementations, the cooking device, as shown in FIGS. 1-7 and 9 includes a round-corner rectangular vent in a top middle portion. In some implementations, a side of the cooking device, as shown in FIGS. 1-5 and 7 includes a rectangular elongated smoke assembly with a pivoting lower half. In some implementations, the front side of the cooking device, as shown in FIGS. 1-3, 7, and 8 includes a handle on a middle portion of the front side to open a lid of the cooking device. In some implementations, the front side of the cooking device, as shown in FIGS. 1-3, 7, and 8 includes a control panel on a lower portion of the front side.

The broken lines shown in the figures show features of the cooking device that form no part of the claimed design.
